UNITED STATES PATENT OFFICE.

REYNOLDS C. FRAMPTON, OF PITTSBURGH, PENNSYLVANIA, ASSIGNOR TO PITTSBURGH WATER HEATER COMPANY, OF PITTSBURGH, PENNSYLVANIA, A CORPORATION OF NEW JERSEY.

INSTANTANEOUS WATER-HEATER.

1,133,016.

Specification of Letters Patent. Patented Mar. 23, 1915.

Application filed October 12, 1908. Serial No. 457,383.

To all whom it may concern:

Be it known that I, REYNOLDS C. FRAMPTON, a citizen of the United States, residing at Pittsburgh, in the county of Allegheny and State of Pennsylvania, have invented certain new and useful Improvements in Instantaneous Water-Heaters, of which the following is a specification.

The invention relates to instantaneous water heaters, and has for its principal objects; the provision of an apparatus of this character employing a circulatory outside thermostat wherein improved controlling or checking means are provided for permitting free and unimpeded circulation through the thermostat and its connections when the outlet from the heater is closed and which will be positively actuated to prevent any direct flow of cold water to the outlet from the inlet when the outlet is closed; the provision of checking means of the character specified which will operate even when only a limited flow occurs from the outlet; and the provision of an apparatus of the character specified wherein a return circulation to the heater is provided for. One embodiment of the invention is illustrated in the accompanying drawings, wherein:—

Figure 1 is a front view of the heater.

Figure 2 is a side elevation thereof,

Figure 3 is an enlarged detail view, partially in section of the controlling mechanism;

Figure 4 is an enlarged detail partly in section of the improved controlling valve, the section being taken on the line IV—IV of Figure 3,

Figure 5 is a sectional view similar to that of Figure 4, but with the piston valve in its upper position, and

Figure 6 is a sectional view similar to that of Figure 4, showing a modified form of check valve.

Referring first to the general arrangement of parts as shown in Figures 1, 2 and 3, 1 is the casing of the heater, 2, 3 and 4 are the upper sets of coils of the boiler, 5 is the lower inverted set of coils, the lower coil of which set is connected to the lower coil of the set 4 by means of the pipe 6, 7 is the thermostat casing, which casing communicates with the upper coil of the set 5 by means of the pipe 8, and is provided with an outlet 9 for the hot water which is to be distributed, 10 is

the gas inlet pipe provided with the usual manually operated valve 11, 12 is the gas valve casing, the valves of which are automatically controlled from the thermostat and water valve in a manner to be herein-after described, 13 is the gas pipe leading from the valve 12 to the burners, 14 is water supply pipe leading to the automatic water valve casing 15, 16 is a water pipe leading from the valve casing 15 to the casing 17 of the controlling check valve to be hereinafter more particularly described, 18 is a pipe leading from the casing 17 to the upper coil of the set 2, 19 is a tube leading from the upper portion of the casing 17 to the upper portion of the thermostat casing 7, and 20 is a pressure regulating valve whose construction may be of any approved type and is immaterial in so far as the invention of this application is concerned.

By reference to Figure 3 it will be seen that the thermostat casing is provided with the usual thermostat tube 21 carrying a porcelain rod 22 for operating the levers 23 and 24. The gas valve casing 12 is provided with a pair of disks 25 and 26 operated respectively by the tube 27 and rod 28. The rod and tube move independently of each other, the tube being operated from the thermostat lever 24, and the rod being operated by the rod 29 of the water valve. The rod 29 is carried by the piston 30 of the water valve, which piston is normally held in the position shown in Figure 3 by means of the spring 31. When no water is being drawn from the heater and the temperature of the water in the thermostat casing 7 is below a maximum, the valve disks 25 and 26 occupy the positions illustrated in Figure 3. If the outlet to the tube 16 is opened, the pressure upon the left hand end of the piston 31 of the water valve moves such piston to the right and its stem or rod 29 actuates the rod 28 to open the disk 26 against the pressure of the spring 32. When the water in the thermostat casing 7 rises above a maximum for which it is set, the copper tube 21 moves upward a sufficient distance to permit the spring 33 to close the valve disk 25, thus cutting off the supply of gas to the burners even though the disk 26 should remain open.

The construction of the controlling check valve is illustrated most clearly in Figures 4 and 5. By reference to these figures it

will be seen that the casing 17 is provided with an inlet passage 34 and a pair of circulation passages 35 and 36, leading respectively to the connection 18 to the upper coil 5 of the boiler, and to the connection 19 leading to the thermostat casing 7. Screw threaded into the end of the casing 17 is a bushing 37, and slidably in this bushing is a piston valve having the two heads 38 and 39. The bushing is also provided with two ports 40 and 41 leading respectively to the passages 35 and 36. The piston valve is held normally in the position shown in Figure 4 with its head covering the feed port 34 by means of the spring 42. The valve parts occupy the positions shown in Figure 4 when no water is being drawn through the outlet pipe 9. With the parts in this position, water from the inverted or reverse coil 5 may circulate freely to the upper coil 2 through the connection 8, the casing 7, the connection 19 and the ports and the passages of the valve casing 17 to the connection 18. In other words, a free and unobstructed circulatory passage is provided from the lower coil to the upper coil by the thermostat casing and an effective circulation of water may occur even when the outlet 9 is closed, thus insuring a control of the thermostat and the gas valve by the hottest water in the boiler. A return circulation to the boiler is also provided for by means of the pipe 43, and a continuous double circulation may be maintained, a part of the water from the thermostat casing passing up through the outlet 9 and around through the system and back through the return pipe 43, while another portion passes through the connection 19 to the casing 17 and then back to the upper coil of the boiler. If the outlet through the pipe 9 is opened, the piston valve will assume the position shown in Figure 5 by reason of the unbalanced pressure on the opposite sides of such valve, and the up-flow through the inlet pipe 16. When the parts are in this position the water from the pipe 16 will pass through the valve casing 17 and out through the passage 35 and connection 18 to the upper coil of the boiler, and thence through the coils of the boiler, the thermostat casing 7 and the outlet pipe 9. It will be noted that when the parts are in the position of Figure 5, there is no possibility of a flow of cold water from the casing 17 to the thermostat casing 7, as the valve heads 38 and 39 close off the upper portion of the bushing from the lower portion and prevent any flow through the passage and connection 19 to the thermostat casing 7. In this manner any cold water is prevented from mingling with the hot water flowing out through the outlet 9. The use of the two valve disks 38 and 39 is advantageous, in that the head 39 closes communication to the upper portion of the bushing 65 and the port 41 before there is any opportunity of a flow to the upper side of the head 38, and the tendency to displace the valve after it is once seated in the position of Figure 5 is reduced, as the area of the upper head 39 which is exposed to pressure from above, is much less than the area of the head 38 which is exposed to pressure from below. When the outlet from the pipe 9 is closed, the pressure on the lower side of the head 38 is of course reduced, and the spring 42 serves to return the valve to the position of Figure 4, in which position a clear passage is afforded between the upper end of the thermostat casing and the upper end of the boiler. The piston controlling or check valve as heretofore described is superior to the ordinary check valve which might be employed, not only because of the unobstructed passage afforded for circulation 85 when the outlet from the thermostat is closed, but because of the more positive action due to the fact that the valve is in the line of flow through the inlet and must be moved up to a position closing off the connection to the thermostat before any flow to the boiler can occur. Any uncertainty in the operation of the valve is thus avoided, and when once moved to upper closed position it is securely maintained in such position even under light or varied supply pressure until the outlet from the thermostat is closed.

It will be understood that the invention is not limited to the particular form of boiler 100 illustrated having the reverse lower coil although this is the preferred arrangement as the upward circulation through the thermostat casing is insured. When the ordinary type of instantaneous water heater 105 boiler without the reverse coil is employed, the circulation might at times be in the reverse direction, *i. e.* upward through the coils and downward through the thermostat casing and under these conditions an unimpeded circulation through the valve casing 17 is still permitted when the outlet from the thermostat casing is closed as circulation may occur through the casing 17 as readily in one direction as in the reverse. The use of the controlling check is therefore not limited in its application, and the invention comprehends broadly the use with the boiler and circulating thermostat of the piston valve normally leaving a passage for circulation in both directions between the boiler and the thermostat casing and which is positively operated by the inflow from the feed pipe to cut off the passage to the thermostat casing. It will also be apparent that it is 115 not necessary that the end of the piston valve entirely close the port 34, as all that is necessary is that the end of the valve ob-

struct the passage to such an extent that the inflow will open the valve. A small passage 45 is in fact preferably provided through the head 33 in order to relieve any undue pressure which might accumulate in the boiler.

When the water pressure available for supplying the heater is low, the construction of controlling check valve, illustrated in Fig. 6, is preferable to that of Figures 4 and 5. This valve construction may be readily substituted for that of Figures 4 and 5 by unscrewing the bushing 37 from the casing 17, and inserting in place thereof the bushing 37', which bushing is provided with a valve disk 43 normally held closed by means of a spring 44. It will be seen that with this arrangement there is no valve to lift when the outlet 9 is open, and a flow from the pipe 16 to the passage 35 is desired. This is desirable with low pressures, as a considerable amount of the flow is cut down under such conditions where a valve such as that of Figure 4 is used, which valve must be raised by the low pressure available. Even where the tension of the spring 42 is reduced or entirely eliminated, the action of the valve of Figure 4 is not satisfactory under lower pressures as the return of the valve to its seat is uncertain, and the pressure and flow are still cut down to a considerable extent. The valve 43 of Figure 6 is held closed with a very small degree of force, so that the circulation through the casing 7 and casing 17 to the heater is not cut off, although slightly reduced when the outlet 9 is closed. This style of valve is obviously not so well adapted to systems employing a return circulation pipe as the valve of Figure 4, for the reason that substantially all of the circulation will be diverted through the return circulation pipe instead of passing to the upper coil through the connection 18. With the valve of Figure 4, the return of a part of the water to the upper coil through the passage 18 is insured under these conditions as there is no resistance to the passage of the water through the casing 17.

Having thus described my invention and illustrated its use, what I claim as new and desire to secure by Letters Patent is the following:

1. The combination with a thermostat, of a vertical coil tube boiler having an inlet to the upper portion and an outlet from the lower portion passing to the thermostat, a service outlet from the thermostat, a communication from the thermostat to the upper portion of the boiler, and automatic controlling means for the communication and boiler inlet arranged to permit communication between the thermostat and boiler in both directions when the outlet from the

thermostat is closed and to close the communication from the boiler inlet to the thermostat when the outlet from the thermostat is opened.

2. The combination with a thermostat, of a vertical coil tube boiler having upper and lower sections and an inlet to the upper section, a connection from the lower end of the upper section to the lower end of the lower section, an outlet from the upper end of the lower section passing to the thermostat, a service outlet from the thermostat, a communication from the thermostat to the upper portion of the boiler, and automatic controlling means for the communication and boiler inlet arranged to yieldingly maintain communication between the thermostat and boiler in both directions when the outlet from the thermostat is closed and to permit a flow through the boiler inlet and close the communication from said boiler inlet to the thermostat when the outlet from the thermostat is opened.

3. The combination with a thermostat, of a coil tube boiler having an inlet to the upper portion and an outlet from the lower portion passing to the thermostat, a service outlet from the thermostat, a valve casing in the said inlet, a communication from the casing to the thermostat, and a piston valve arranged to yieldingly obstruct the flow to the boiler from the said inlet and permit communication between the thermostat and boiler when the outlet from the thermostat is closed, and to be moved by the inflow to open the said inlet and close the communication therefrom to the thermostat when the outlet from the thermostat is opened.

4. The combination with a thermostat, of a coil tube boiler having an inlet to the upper portion, and an outlet from the lower portion passing to the thermostat, a service outlet from the thermostat, a communication from the thermostat to the upper portion of the boiler, and automatic controlling means for the communication and said inlet arranged to yieldingly obstruct the inlet and permit communication between the thermostat and boiler in both directions when the outlet from the thermostat is closed and to be moved by the inflow through the said inlet and close the communication therefrom to the thermostat when the outlet from the thermostat is opened.

5. In heating apparatus, the combination with a coil tube boiler provided with gas heating means, a thermostat casing having a hot water outlet leading from the apparatus, a thermostat in the casing arranged to control the flow of gas to the heating means, an outlet connection from the boiler to the casing, and a pipe for supplying water to the apparatus, of a valve casing having communicating connections with the

supply pipe, the thermostat casing and the boiler provided with a valve yieldingly held with its end in position to obstruct the supply connection with the other connections 5 in communication and arranged so as to be moved by the inflow to a position closing the connection with the thermostat casing and placing the supply pipe and connection to the boiler in free communication when 10 the outlet from the thermostat casing is opened.

6. In heating apparatus, the combination with a coil tube boiler provided with gas heating means, of a thermostat casing provided with a thermostat for controlling the supply of gas to the heating means and having a connection to the boiler and a hot water service outlet leading from the apparatus, a valve casing having a feed port 15 and two other ports having connections leading respectively to the thermostat casing and heater, and a piston valve yieldingly held with its end over the feed port with the other two ports uncovered and 20 communicating, and adapted when the outlet from the thermostat casing is opened and the pressure on the opposite ends of the valve unbalanced to move so as to close the port connected to the thermostat casing and 25 place the feed port and the port connected to the boiler in free communication.

7. In heating apparatus, the combination with a coil tube boiler provided with gas heating means, of a thermostat casing 30 provided with a thermostat for controlling the supply of gas to the heating means and having a connection to the boiler and a hot water service outlet leading from the apparatus, a valve casing having a feed port 35 and two other ports having connections leading respectively to the thermostat casing and heater, and a piston valve with its end yieldingly held over the feed port with the other two ports uncovered and communicating, and adapted when the outlet from 40 the thermostat casing is opened and the pressure on the opposite ends of the valve unbalanced to move so as to first close the port connected to the thermostat and after 45 such closure place the feed port and the port connected to the boiler in free communication.

8. In heating apparatus, the combination with a vertical coil tube boiler provided 50 with gas heating means of a substantially vertical thermostat casing provided with a thermostat for controlling the supply of gas to the heating means, and having a connection from its lower portion to the lower portion 55 of the boiler and a hot water service outlet from its upper portion leading from the apparatus, a valve casing having a feed port and two other ports having connections leading respectively to the thermostat 60 casing and the upper portion of the boiler,

and a piston valve in alignment with the feed port and arranged to normally obstruct such port, the ports and valve being so arranged that when the outlet from the thermostat is closed the end of the valve is 70 over the feed port and the other ports are uncovered and communicating, and when such outlet is opened the valve is moved to close the port connected to the thermostat casing and permit a flow between the other 75 two ports in communication.

9. In heating apparatus, the combination with a vertical coil tube boiler having a reverse coil at its lower end and provided with gas heating means, a thermostat casing connected to the upper end of the reverse coil and having a hot water service outlet leading from the apparatus, a thermostat in the casing arranged to control the flow of gas to the heating means, and a pipe for supplying water to the apparatus leading to the upper portion of the boiler, of a valve casing having communicating connections with the supply pipe, the thermostat casing and the boiler, and provided with a valve 80 normally seating itself so as to cover the supply opening and leave the other connections in communication, and adapted to be moved to position closing the connection with the thermostat casing and placing the supply pipe and connection to the boiler in free communication when the outlet from the thermostat is opened.

10. In heating apparatus, the combination with a vertical coil tube boiler having a reverse coil at its lower end and provided with gas heating means, a thermostat casing connected to the upper end of the reverse coil and having a hot water service outlet leading from the apparatus, a thermostat in the casing arranged to control the flow of gas to the heating means, and a pipe for supplying water to the apparatus leading to the upper portion of the boiler, of a valve casing having communicating connections with the supply pipe, the thermostat casing and the boiler and provided with a valve adapted to cut off the connection between the valve casing and thermostat casing when the outlet from the thermostat casing is 100 opened, and at other times permit a circulation between the boiler and thermostat casing through the valve casing.

11. In heating apparatus, the combination with a coil tube boiler having a reverse coil at its lower end and provided with gas heating means, a thermostat casing connected to the upper end of the reverse coil and having a hot-water service outlet leading from the apparatus, a thermostat in the casing arranged to control the flow of gas to the heating means, and a pipe for supplying water to the apparatus leading to the upper portion of the boiler, of a valve casing having 110 communicating connections with the sup-

ply pipe, the thermostat casing and the boiler, and provided with a spring held valve adapted to cut off the connection between the valve casing and thermostat casing when the outlet from the thermostat casing is opened, and at other times permit a circulation between the boiler and the thermostat casing through the valve casing.

12. In heating apparatus, the combination with a vertical coil tube boiler having a reverse coil at its lower end and provided with gas heating means, a thermostat casing connected to the upper end of the reverse coil and having a hot-water service outlet leading from the apparatus, a thermostat in the casing arranged to control the flow of gas to the heating means, and a pipe for supplying water to the apparatus provided with an automatic water valve for controlling the

flow of gas to the heating means, of a valve casing having communicating connections with the supply pipe, the thermostat casing and the boiler, and provided with a spring held valve adapted to cut off the connection between the valve casing and thermostat casing when the outlet from the thermostat casing is opened, and at other times permit a circulation from the thermostat casing to the valve casing and thence to the boiler.

13. In heating apparatus, the combination with a thermostat, of a coil tube boiler having an inlet to the upper portion and an outlet from the lower portion passing to the thermostat, a valve casing in the inlet, a communication from the casing to the thermostat, a piston valve in the line of flow through the valve casing to the boiler arranged to yieldingly obstruct the flow to the boiler from the inlet and permit communication between the thermostat and boiler when the outlet is closed, and when such outlet is opened to be moved by the pressure against the end to open so as to permit a free flow from the inlet and by such move-

ment close the communication to the thermostat.

14. In heating apparatus, the combination with a thermostat, of a coil tube boiler having an inlet to the upper portion and an outlet from the lower portion passing to the thermostat, a hot-water service outlet leading from the thermostat, a communication from the thermostat to the upper portion of the boiler, and automatic controlling means for the communication and inlet arranged to yieldingly obstruct the inlet and permit communication between the thermostat and the boiler when the service outlet from the thermostat is closed and to close the communication from the inlet to the thermostat when the service outlet from the thermostat is opened.

15. In heating apparatus, the combination with a coil tube boiler provided with gas heating means, a thermostat casing connected to the lower portion of the boiler and having a hot water service outlet leading from the apparatus, a thermostat in the casing arranged to control the flow of gas to the heating means and a pipe for supplying water to the apparatus leading to the upper portion of the boiler, of a valve casing having communicating connections with the supply pipe, the thermostat casing and the boiler, and provided with a valve adapted to cut off the connection between the valve casing and thermostat casing when the outlet from the thermostat casing is opened, and at other times permit a circulation between the thermostat casing and boiler through the valve casing.

In testimony whereof I have hereunto signed my name in the presence of the two subscribed witnesses.

REYNOLDS C. FRAMPTON.
